UNITED STATES PATENT OFFICE.

PETER J. DESSELLE AND GUSTAVE F. PHILLIPPAR, OF WEIR, KANSAS.

STOOL.

1,129,175.

Specification of Letters Patent. Patented Feb. 23, 1915.

Application filed April 18, 1911. Serial No. 621,793.

To all whom it may concern:

Be it known that we, PETER J. DESSELLE and GUSTAVE F. PHILLIPPAR, citizens of the United States, residing at Weir, in the county of Cherokee and State of Kansas, have invented new and useful Improvements in Stools, of which the following is a specification.

The invention relates to stools, and more particularly to the class of spring tensioned stools.

The primary object of the invention is the provision of a stool in which the seat thereof is tensioned, so as to prevent shocks and jars from being transferred to the occupant of the stool, the stool being especially useful to motormen and other railway men.

Another object of the invention is the provision of a stool in which the seat thereof is readily and easily adjusted to suit the occupant, and that is yieldably supported in its base, so as to prevent vibration of a vehicle from being transferred to the occupant.

25 A further object of the invention is the provision of a stool which is simple in construction, strong, durable, and inexpensive in manufacture.

With these and other objects in view, the 30 invention consists in the construction, combination and arrangement of parts, as will be hereinafter more fully described, illustrated in the accompanying drawings, and pointed out in the claim hereunto appended.

35 In the drawings: Figure 1 is a side elevation of a stool constructed in accordance with the invention. Fig. 2 is a vertical longitudinal sectional view thereof. Fig. 3 is a sectional view on the line 3—3 of Fig. 1. 40 Fig. 4 is a sectional view on line 4—4, of Fig. 1.

Similar reference characters indicate corresponding parts throughout the several views of the drawings.

45 Referring to the drawings by numerals, the stool comprises a base including upwardly converging legs 5, four of which are preferably used, and which are united by cross rungs 6 in the usual well-known manner, the legs, at their upper ends being fitted in suitable sockets formed in the under face of a circular head 7, forming the stool proper.

50 Passing downwardly through a suitable central opening in the circular head 7 of

the stool proper is a revoluble post or stem 8, to the free end of which is fixed a circular shaped seat 9 which may be padded or otherwise upholstered for comfort to the occupant thereof. Secured to the under face 60 of the head 7 and surrounding the stem 8 is a guide sleeve 10 which may be of the required length, the same being formed with a circular flange 11, through which are passed suitable fasteners, securing it to the 65 under face of the head 7 of the stool.

Below the end of the sleeve 10 is a disk 12, provided with a central perforated boss or hub 13, the same being arranged concentrically about the stem 10, and against which 70 abuts a collar 14 carrying a set screw 14' locking it upon said stem 8, thereby adjustably securing the disk 12 on the stem. Suitably secured in the disk 12, near the periphery thereof, are eye members 15, with which are 75 engaged the lower ends of coiled retractile springs 16 arranged in series concentrically about the sleeve 10, the springs 16, at their upper ends, being detachably engaged with hook members 17, suitably secured in the 80 circular shaped flange 11, contiguous to its periphery, the springs being designed to yieldably support the seat 9 when occupied by a person.

Surrounding the stem 8 and adapted to 85 abut against the lower end of the sleeve 10 is an adjustable collar 18, the latter carrying the usual set screw 19, whereby it may be adjusted on the stem, and this collar is designed to limit the upward sliding movement of the stem 8 in the sleeve 10 when the seat is unoccupied. It is of course understood that the collar 14 may be otherwise 90 adjustably connected with the stem 8, and likewise the collar 18, if found desirable. It 95 will be obvious that when the seat is occupied, all vibration of a vehicle will be absorbed, thereby preventing the same from being transferred to the occupant of the stool, the latter being especially useful for 100 motormen and other railway men.

What is claimed is:

A stool of the class described, comprising a base frame provided with a circular head, a sleeve provided with a flange attached to 105 the under surface of the head, a seat, a stem depending centrally from said seat and slidably mounted in said sleeve and head, a disk slidably mounted on the stem adjacent its free end, a collar adjustably secured to said 110

stem above the said disk for limiting the upward movement thereof, a second collar adjustably mounted on the stem above and abutting the free end of the sleeve for limiting the upward movement of the said seat, stem and disk, springs connected to the flange on the sleeve and the disk for yieldingly supporting a weight on said seat, said first mentioned collar and disk allowing the

simultaneous adjustment of all of the 10 springs to any degree of resiliency.

In testimony whereof we affix our signatures in presence of two witnesses.

PETER J. DESSELLE.

GUSTAVE F. PHILLIPAR.
